UNITED STATES PATENT OFFICE.

WILLIAM W. ROBERTSON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

CENTER SUPPORT FOR TUBE FRAMES.

Application filed March 26, 1924. Serial No. 702,137.

To all whom it may concern:

Be it known that I, WILLIAM W. ROBERTSON, a subject of the King of Great Britain, residing at Worcester, in the county of Worcester and State of Massachusetts, have invented a new and useful Center Support for Tube Frames, of which the following is a specification.

This invention relates to wide Axminster looms in which the tuft yarn is presented to the warp by a plurality of tube frames on which the yarn spools and yarn tubes are mounted. The increased width of such looms has caused a corresponding increase in the length of the tube frames. Difficulty has been encountered in the use of these long tube frames, as they are commonly supported at the ends only and have been found to sag or bend in the middle portion to such an extent that they interfere with other movable parts of the loom and are thereby frequently injured.

It is the object of my invention to provide a center support or guide for such tube frames, by which they will be held from downward displacement between the ends thereof.

My invention further relates to arrangements and combinations of parts which will be hereinafter described and more particularly pointed out in the appended claims.

A preferred form of the invention is shown in the drawings in which—

Fig. 1 is a front elevation of a portion of an Axminster loom embodying my improvements;

Fig. 2 is a transverse sectional elevation, taken along the line 2—2 in Fig. 1;

Fig. 3 is a view similar to Fig. 2 but showing the parts in a different position;

Fig. 4 is an enlarged detail front elevation of a center portion of a tube frame, and

Fig. 5 is a sectional elevation taken along the line 5—5 in Fig. 4.

Referring to the drawings, I have shown a portion of a loom frame 10 in which is rotatably mounted a shaft 11 having guide pulleys or sprockets 12 for the chains 13 which present and transport the tube frames 14. Yarn spools 15 are rotatably mounted on each tube frame and each frame is provided with ears or brackets 16 by which it

is detachably secured to the chains 13. All of these parts are of the usual type. 55

My improved center support is shown as taking the form of a disc 20 secured to the shaft 11 in some convenient manner, as by set screws 21 (Fig. 2). The disc 20 is provided with a series of recesses or notches 23, 60 each adapted to receive the rounded head or end 24 of a special center spool bearing 25 (Figs. 4 and 5). This bearing 25 is made in one piece and the spools 15 adjacent thereto are preferably provided with bearing studs 26, each of which extends approximately one half way through the bearing 25.

The operation of my improved center support is clearly indicated in Figs. 2 and 3, in which it will be seen that the recesses 70 23 receive the rounded heads 24 of the center bearings 25 and continuously support the center of the tube frame from downward displacement as the chains 13 carry the tube frames around the guide pulleys 12. 75 With this construction, the tube frames are held substantially straight during their movement around the shaft 11 and they are thus prevented from getting into the path of other moving parts of the loom, by which 80 they might be seriously damaged.

Having thus described my invention and the advantages thereof, I do not wish to be limited to the details herein disclosed otherwise than as set forth in the claims, but 85 what I claim is:—

1. In a loom, a yarn tube frame, chains to support the ends of said frame, and means to engage and support the center of said frame during movement by said chains adjacent the point of presentation of the tube frame and yarn to the fabric. 90

2. In a loom, a yarn tube frame, chains to support the ends of said frame and means to prevent sagging of said frame between 95 its ends during movement by said chains adjacent the point of presentation of the tube frame and yarn to the fabric.

3. In a loom, a yarn tube frame, chains to support the ends of said frame, and a 100 recessed rotatable member engaging said frame near the center thereof and supporting said frame during movement by said chains adjacent the point of presentation of the tube frame and yarn to the fabric. 105

4. In a loom, a yarn tube frame, chains

- to support the ends of said frame, sprockets for said chains, a shaft to which said sprockets are fixed, and a recessed disc fixed near the center of said shaft and engaging and supporting said frames during movement by said chains adjacent the point of presentation of the tube frame and yarn to the fabric.
5. In a loom, a yarn tube frame chains 10 to support the ends of said frame, and means to engage and support the center of said tube frame during movement by said chains adjacent the point of presentation of the tube frame and yarn to the fabric, said tube frame having an intermediate spool bearing with a rounded end and said means comprising a positively rotated member recessed to receive the rounded end of said projection.
- 15 6. In a loom, transporting chains, yarn tube frames connected to said chains, and means to support the frames intermediate the ends thereof when said frames are connected to the chains and adjacent the point 20 of presentation of the tube frame and yarn to the fabric.
7. In a loom having transporting chains, a series of yarn tube frames traveling with the chains and movable one by one from 25 said chains toward and from weaving position, and means to engage the intermediate portions of certain of the frames located in the chains adjacent the point of presentation of the tube frame and yarn to the 30 fabric and hold said portions clear of the frame which is moving toward and from weaving position.
8. In a loom, a series of yarn tube frames 35 movable one by one toward and from weaving position, and means acting on the intermediate portions of certain of the frames in non-weaving position but adjacent the point of presentation of the tube frame and yarn to the fabric to hold said intermediate 40 portions out of the path of the frame which is moving toward and from weaving position.
9. A yarn tube frame for Axminster looms having transporting chains and a tube 45 frame supporting member intermediate the chains, said tube frame having spool bearing brackets on the ends thereof affording a connection between the chains and the frame, and having also a spool bearing bracket intermediate the ends thereof pro-
- vided with an interior bearing for the spools and an exterior bearing surface to cooperate with the supporting member while the tube frame is connected to the chain and adjacent the point of presentation of the 60 tube frame and yarn to the fabric.
10. In a loom, transporting chains, yarn tube frames attached to and movable with the chains, sprockets for the chains to hold the ends of the frames in spaced relationship, a shaft to which said sprockets are secured, and means to engage the intermediate portions of said tube frames to hold said intermediate portions in substantially the same relationship as that in which the 65 ends of the frames are held by the sprockets while said frames are attached to said chains and are adjacent the point of presentation of the tube frame and yarn to the fabric.
11. In a loom, a series of yarn tube frames 70 movable one by one to weaving position, yarn spools, a bearing member intermediate the ends of each frame having an internal bearing surface for yarn spools and an external bearing surface, and means to engage the external bearing surface of the frames in non-weaving position but adjacent the point of presentation of the tube frame and yarn to the fabric to hold the intermediate portions of the said frames out of the 75 path of the frame which is moving toward and from weaving position.
12. A center support for the yarn tube frames of looms having a series of tube frames arranged to pass by the support as 80 the loom operates and movable one by one to weaving position, said support having a surface to engage the tube frames out of weaving position but adjacent the point of presentation of the tube frame and yarn to the 85 fabric and hold the same clear of the frame which is in weaving position.
13. A center support for the yarn tube frames of looms having a series of tube frames arranged to pass by the support as 90 the loom operates, said support having a plurality of surfaces to engage the frames while the latter are in proximity to the support and adjacent the point of presentation of the tube frame and yarn to the fabric 95 and to brace the same against downward deflection.
- In testimony whereof I have hereunto affixed my signature:
- WILLIAM W. ROBERTSON.
